UNITED STATES PATENT OFFICE.

PARK A. HERR, OF HILLSIDE, NEW JERSEY, ASSIGNOR TO THE SINGER MANUFACTURING COMPANY, A CORPORATION OF NEW JERSEY.

THREAD-CONTROLLING MECHANISM FOR SEWING MACHINES.

1,402,930.

Specification of Letters Patent. Patented Jan. 10, 1922.

Application filed June 11, 1918. Serial No. 239,369.

To all whom it may concern:

Be it known that I, PARK A. HERR, a citizen of the United States, residing at Hillside, in the county of Union and State of New Jersey, have invented certain new and useful Improvements in Thread-Controlling Mechanisms for Sewing Machines, of which the following is a specification, reference being had therein to the accompanying drawings.

This invention relates to sewing machines and particularly to mechanism used in conjunction therewith for controlling the thread as it passes to the stitch-forming mechanism for assisting the same in perfecting the stitch.

In the evolution of a modern take-up for sewing machines it has been found that any required thread-control may be obtained by the use of a properly designed cam (usually of a barrel or face type) to actuate a thread-engaging member, but such take-ups are defective in one particular, to wit, they limit the speed of operation of the machine. Further development evolved the link actuated take-up which is in extensive use to-day because it is capable of operation at a high speed but it is defective because it lacks the nicety of thread control which is desirable and which has been obtained with the cam-actuated take-up.

The present invention aims to improve the construction and operation of the link-actuated type of take-up by a combination and arrangement of links and levers which permit operation of the machine at a high speed and which also possesses the nice thread control that is the desideratum at the present day.

Essentially the invention comprises a take-up arm pivoted on the head of the machine with its apertured thread-engaging end vibrantly arranged at the front of the machine head. The arm is oscillated through a link from a lever which is fulcrumed eccentrically on a rotary disk within the head of the machine and while the lever is being bodily rotated it is swung about its fulcrum so as to carry a pin connecting the link and lever to and from the axis of the disk to vary its action, such swinging motion being effected by articulating the other end of the lever to a strap which embraces a stationary disk disposed eccentrically of the axis of the rotary disk. The pin connection between the link and lever moves in an ap-

proximately heart-shaped path the resultant of two combined circularly movable elements and through the pin connection the end of the take-up arm is vibrated in a 60 fashion controlling the thread nicely throughout each stitch-forming cycle of operations. The mechanism is simple, durable, capable of operation at a high speed, once adjusted is not likely to vary in its co-operative action with the stitch-forming mechanism during the life of the machine and constitutes a marked advance in the art.

The invention is illustrated in the accompanying drawings, in which Fig. 1 represents the link actuated take-up applied to a lock-stitch machine, the parts being shown in end elevation in the relative position they occupy when the needle-eye is at the level of the throat-plate. Fig. 2 the same just 70 after the loop-taker has entered the needle-loop. Fig. 3 the same at the commencement 75 of cast-off. Fig. 4 the same when the stitch is completely set. Fig. 5 shows the construction in front elevation. Fig. 6 is a section 80 on the line A—B, Fig. 5. Fig. 7 is a sectional detail of the actuating crank-pin. Fig. 8 is a diagram representing the relative movement of the take-up and needle-eyes. Fig. 9 is a motion diagram representing 85 graphically the various positions assumed by the several joints of the linkage actuating the take-up during a stitch-forming cycle of operation.

In the drawings the invention is illustrated applied to a machine of a lock-stitch type having a needle 1 on a needle-bar 2 reciprocated through a link 4 from a crank-pin 5 radially spaced from the axis of a disk 6 which is fast on a driving shaft 7 95 mounted in bearings in the overhanging arm 8 and terminating in the head 9. A presser-foot 10 is carried by a bar 11 and cooperates with a feed-dog (not shown) to advance the work a stitch length at a time in a manner 100 well known.

Below the plane of the work-support and throat-plate is a loop-taker or hook 12 and bobbin 13 which in the machine illustrated are of the oscillatory type and cooperate 105 with the needle in a well understood fashion but a rotary type may be used if desired. Any suitable mechanism may be used to impart the requisite motion to the loop-taker or hook 12 to insure cooperation thereof 110 with the needle.

A thread-engaging element 15, constitut-

ing the vital element of the thread-control-
ling mechanism, is fulcrumed on a pin 16 in
the rear of the head of the machine with its
body free to vibrate in a plane slightly to
5 one side of and parallel with the needle-bar
and with its free apertured end 17 extending
to the front of the machine. An arm 18
firmly secured on the other end of the pin
16 is connected by a link 19 to an arm 20
10 fast on one end of the crank-pin 5 to whose
opposite end is likewise fast a second arm
21. A pin 19' loosely connects the link 19
and arm 20. The arm 21 is loosely joined
by a pin 22 to a strap 23 which embraces
15 a stationary disk or eccentric 24 integral or
otherwise fixed to a sleeve 25 encircling the
driving shaft 7 and secured for angular ad-
justment thereabout by the clamp-screw 26
which is threaded into the overhanging arm
20 of the machine. If desired the stationary
disk 24 may be made adjustable to vary its
throw i. e., the distance between the centers
C—C and C—D, Fig. 9, by any suitable
25 mechanical expedient of which there are a
great variety known to those skilled in the
art.

Upon the front side of the head and over-
hanging arm of the machine threaded-guid-
ing devices are mounted. These devices
30 comprise constant tensions 27—28, an auto-
matic thread-check 29 (which may be omitted
if desired), a thread-guiding roller 30
and a fixed thread-eye 31. The thread passes
from the supply through the tensions 27—28
35 and automatic thread-check 29 and thread-
guiding roller 30 to the apertured end 17 of
the thread-engaging member of the take-up
and thence through the fixed eye 31 to the
eye of the needle.

40 In the operation of the machine the needle
passes through the work W and shortly after
it starts to ascend throws out a loop of
thread that is entered by the loop-taker 12
which carries the needle-loop to a position,
45 such as shown in Fig. 3, where the loop of
thread is shed or cast off, encircling the
bobbin-thread to form the lock-stitch as is
well understood.

In Fig. 8 the curves of the needle and
50 take-up together with the motion diagram
in Fig. 9 portray the action of the linkage
operating the take-up better than words can
describe. From a consideration of these
figures it will be seen that the take-up acts to
55 set the stitch after the needle has been
started down at that stage in the cycle of
stitch-forming operations indicated by the
arrow C, Fig. 8. While the needle descends
to and through the work thread is given up
60 first at an accelerated rate and then in a re-
tarded rate, its movement being slowest
about the time the needle-loop is entered by
the loop-taker which occurs just before the
parts reach the position shown in Fig. 2 and
65 at that stage in the cycle of operations in-

dicated by the arrow D, Fig. 8. At this
time there is little, if any, slack in the
thread. After the loop is entered by the
loop-taker and while it is being carried and
spread around the bobbin, the thread is 70
rapidly given up in almost exactly the quan-
tity demanded to suit the considerable length
thereof required to pass around the bobbin.
When the loop-taker arrives at cast-off or
shedding position, at that stage in the cycle 75
of operations indicated by the arrow E, Fig.
8, the thread is in the condition illustrated
in Fig. 3, there being no more excess slack
at this time than is prudent to allow as a
factor of safety. After cast-off the parts 80
move from the position shown in Fig. 3 to
that shown in Fig. 4, the thread-engaging
member 15 rising from its lowest to its
highest position and setting the stitch.
Most of the quantity of thread required to 85
pass around the bobbin is taken up in a cir-
cular movement of the driving shaft 7
through an angle of about 45°, the small
quantity of thread remaining being taken up
and the stitch set easily and gradually dur-
ing the succeeding 45° turn of the driving 90
shaft. Thus the critical stage in handling
the thread is performed with a nicety, force
and care that is obviously desirable.

It is to be noted that there is not enough 95
slack in the needle-thread to permit it to
curl under the point of the descending needle
when it is about to enter the work and that
piercing or breaking of the thread in this
way is thus provided against. It is also 100
noted that there is an approach to a dwell
in the down stroke of the take-up at the
time the loop-taker enters the needle-loop
and that the function of this dwell approxi-
mation or retardation is to prevent an excess 105
amount of slack thread between the work
and the thread engaging member 15 in order
to prevent the thread from becoming tangled
about the end of the member or other pro-
jecting portions of the machine in prox-
imity with the take-up. In short the thread
is controlled substantially in the manner that
it has been controlled heretofore with cam-
actuated take-ups by a linkage which does
not, however, limit the speed at which the 115
machine may be operated.

For the convenience of those skilled in
the art it is to be noted that the dimensions
shown in Fig. 9 of the original drawing
are in full size, that the circle whose center
is marked C—D represents the path of the
crank-pin 5, and that the circle whose center
is marked C—C represents the path of
the actuated end of the arm 21 of the bell-
crank 20—5—21. The different positions of 120
the linkage points are indicated by the nu-
merals from 1 to 8, exponents being ap-
pended to the several series of numbers to
distinguish the several joints of the linkage
from one another.

The distinguishing feature of the present invention as it is comprehended at this time resides in the idea of shifting the connection 19' between the arm 20 and the link 19 while it is rotating, said connection constituting what may be loosely termed a shiftable crank-pin which has a combined rotary and transverse movement with respect to an imaginary axis coincident with the axis of the driving shaft 7.

The path of the connection 19' between the link 19 and arm 20 is nearly heart-shape and is the resultant of rotating the fulcrum of the bellcrank-lever 20-5-21 about the axis 15 of the shaft 7 with an end of one arm of the bellcrank lever confined to move in a circular path eccentric to the path of the crankpin 5. In other words the actuated end of the link 19 is moved in a path the resultant 20 of two circularly moving elements in eccentric relation.

In the drawings and in the foregoing description the construction has been described specifically with a view to enabling those skilled in the art constructing and compounding the same, but it is to be distinctly understood that the principle of the invention is not confined to the specific proportion and arrangement of the parts. Obviously it may be used to handle looper-threads as well as needle-threads, its position upon the head of the machine (when used there) may be varied, the relative proportions of the several members of the linkage may be varied to alter the action of the thread-engaging member upon the thread. The lever 15-16-18 and the bellcrank 20-5-21 may be of the first, second or third order if desired. The driving shaft 7 in the machine illustrated rotates but the invention might be applied to a machine whose corresponding shaft is oscillated or rocked. These and many other changes might be effected without departing from the principle of the invention which is capable of extensive modification because of the changes in the action of the linkage which result, as I have discovered, from varying the angular relation of the disks 6 and 24 relative to the axis of the shaft 7 and the spacing of their centers and from varying the relative lengths of the arms and link, and also from varying the relation and distance between the axes of pin 16 and shaft 7.

Having thus set forth the nature of the invention, what I claim herein is:

1. In a sewing machine, in combination with stitch-forming mechanism, thread controlling mechanism including a thread-engaging member, means for moving the thread-engaging member to govern the thread as demanded by the stitch-forming mechanism in perfecting the stitch including a link connected to the thread-engaging

member, and means for imparting to said link a movement whereby a point on said link spaced from said connection will have a combined rotary and transverse movement with respect to an imaginary axis during 75 each stitch-forming cycle of operations, said latter means comprising a crank mounted on a pivot movable in a curved path, and means for turning the crank on the pivot as it traverses said path.

2. In a sewing machine, in combination, stitch-forming mechanism and thread controlling mechanism including a thread-engaging member, a link operatively connected through one of its ends to the thread-engaging member, a rotary shaft, a lever fulcrumed eccentrically of said shaft and movable both with and independently of said shaft and having one of its ends connected to said link, and means for operating 80 the lever to obtain an angular rotation of the lever about its own fulcrum while said shaft rotates the fulcrum of the lever whereby the thread-engaging member connected to the other end thereof may be made to control the thread passing to the stitch-forming mechanism to perfect the formation of each stitch.

3. In a sewing machine, in combination, 95 stitch-forming mechanism, and thread-controlling mechanism including a thread-engaging member, a link connected at one end to the thread-engaging member, a member operatively connected to the other end of the link, said member being movable about an imaginary axis, and means for moving said member about said imaginary axis and simultaneously varying its eccentricity relative to the axis in order to accelerate and retard the action of the thread-engaging member to suit the requirements of the stitch being formed.

4. In a sewing machine, in combination, 100 a needle, a shaft connected to and operating the needle, an implement cooperating with the needle to form stitches, thread controlling mechanism including a thread-engaging member, a link at one end pivotally connected to said member, an actuating member connected to the other end of said link, and means for moving said actuating member to and from the axis of said shaft and simultaneously carrying it around with said shaft during a stitch-forming cycle of 105 operations whereby the action of the thread controlling mechanism may be varied as demanded by the cooperating needle and implement to perfect the formation of successive stitches.

5. In a sewing machine, in combination, 110 a needle, a needle-bar, a needle-bar operating shaft, a take-up member, a lever fulcrumed eccentrically of and carried by said shaft, means connecting the lever and take-up, and means for operating the lever to 115

- cause its point of connection with the take-up to rapidly approach, pause and rapidly recede from the axis of the needle-bar actuating shaft whereby the take-up member 5 may be made to control the thread as required.
6. In a sewing machine, in combination, stitch-forming mechanism and thread-controlling mechanism including a thread-engaging member having a fixed fulcrum, and means for operating the thread-engaging member including a shiftable member, a lever carrying said shiftable member, circularly movable elements eccentrically disposed relatively to one another and one of which drives the other, said lever having a portion constituting a link between said circularly movable elements and determining the path and rate of movement of said shiftable member, and a connection between said shiftable member and said thread-engaging member.
7. In a sewing machine, in combination, stitch-forming mechanism including a needle and a shaft for operating the same, and thread-controlling mechanism including a thread-engaging member fulcrumed on a relatively stationary support, an actuating means, a link connecting said actuating means and said thread-engaging member, means for moving said actuating means in a curved path enclosing the axis of the operating shaft whereby the thread-engaging member may be moved to control the thread 30 throughout a stitch-forming cycle of operations.
8. In a sewing machine having stitch-forming mechanism including a needle, a loop-taker and a shaft for operating the same, in combination with thread-controlling mechanism including a thread-engaging member and a linkage for moving the same to give up thread in a gradually decreasing quantity during the descent of the needle 40 and before the loop-taker enters the needle-loop, thereafter to increasingly rapidly give up thread until the loop-taker arrives at cast-off position, then to rapidly take up most of the thread before the needle reaches 45 the upper limit of its stroke, and finally to set the stitch after the needle starts down with a gradually retarded movement.
9. In a sewing machine having stitch-forming mechanism, in combination with a thread-controlling mechanism including a thread-engaging member fulcrumed on a stationary part of the machine, a link connected at one end to said member, a lever which is fulcrumed on a circularly movable 50 element and which is connected at one end to said link, and means for shifting the point of connection between the lever and link during each stitch-forming cycle of operations.
- 65 10. In a sewing machine having stitch-form-

ing mechanism, in combination with thread-controlling mechanism including a thread-engaging member, a link connected at one end to said member, a lever fulcrumed on an arcuately movable element and connected to the other end of said link, and an eccentric element for governing the movement of said lever about its fulcrum during arcuate movement of the fulcrum of the lever with the movable element upon which it is supported. 70

11. In a sewing machine having a needle and loop-taker, in combination, thread-controlling mechanism including a thread-engaging member and link mechanism for operating said member to cause it to decrease its giving up movement when the needle starts to rise and throw out a loop for entrance by the loop-taker, then to cause it to give up thread to the loop-taker until 80 the needle-loop is about to be shed, and finally to cause it to rapidly take up thread immediately after the loop-taker reaches shedding position. 85

12. In a lock-stitch sewing machine having a needle, loop-taker and bobbin, a shaft, a thread-controlling mechanism including a circularly movable element operated by said shaft, a lever fulcrumed on and movable with said circularly movable element, a take-up member linked to one arm of said lever, and means for moving the other arm of said lever toward and from said shaft during circular movement of the fulcrum of the lever with said circularly movable element, 90 whereby the needle-thread may be controlled by the thread-engaging member to meet the requirements of the stitch-forming mechanism during each cycle of operations thereof. 95

13. In a sewing machine, in combination, 100 stitch-forming mechanism including a needle loop-taker and bobbin, and thread-controlling mechanism including a driven shaft, a crank-pin carried thereby and having two arms fixed thereto in an acute angular relation, a strap connected to one of said arms, a stationary disk embraced by said strap and having a circular periphery in non-concentric relation to the path of the crank-pin, a take-up member, and a link connected 110 at its opposite ends to said take-up member and to the other arm on said crank-pin. 115

14. In a sewing machine, stitch-forming mechanism including a needle, a loop-taker and bobbin, and thread-controlling mechanism including a driven shaft, a crank-pin carried thereby and having two arms fixed thereto in acute angular relation, a strap connected to one of said arms, an adjustable stationary disk embraced by said strap and having a circular periphery in non-concentric relation to the path of the crank-pin, a take-up member, and a link connected at its opposite ends to said takeup member and to the other arm on said crank-pin. 120 125 130

15. In a sewing machine having stitch-forming mechanism in combination thread-controlling mechanism including a shaft, a pair of elements confined to circular movement in relatively eccentric paths, a positive connection between said shaft and one of said elements, an arm on one of said elements articulated with the other element, a second arm arranged at an acute angle and fixedly connected to the first mentioned arm with which it forms a lever, a take-up member, and an articulated connection between said second arm and said take-up member for transmitting the throw and arcuate movement of the second arm to the take-up.
16. In a sewing machine, in combination, stitch-forming mechanism and thread-controlling mechanism including a shaft, a crank-pin thereon, arms on opposite ends of said crank-pin forming therewith a lever fulcrumed intermediate its ends, a stationary eccentric loosely embracing said shaft, a strap about said eccentric, said strap and one arm of the lever being articulated together, a take-up member confined to swing in a plane, a link connected to said take-up member and said other arm of the lever.
17. In a sewing machine, in combination, stitch-forming mechanism including a needle loop-taker and bobbin, thread-controlling mechanism including a thread-engaging member, and means for moving said member comprising articulated link lever and two eccentrically disposed circularly movable elements acting upon the fulcrum and one end of said lever to impart the compounded circular movement of the two elements to the other end of the lever.
18. In a lock-stitch machine, an overhanging arm terminating in a head, a needle, a loop-taker, a bobbin, and thread-controlling mechanism including a thread-engaging member fulcrumed on the head, a shaft, a disk on the end thereof within the head, a bellcrank-lever fulcrumed intermediate its ends and eccentrically upon said disk with its arms arranged on opposite sides of said disk, a stationary disk disposed eccentrically of said driven shaft, a strap embracing said stationary disk and articulated to an arm of said bellcrank-lever, and a link connecting the other arm of the bellcrank-lever and the thread-engaging member.
19. In a sewing machine having stitch-forming mechanism including a needle and a shaft for operating the same, a thread-controlling mechanism including a thread-engaging member, a link connected at one end to said member and having its other end confined to move in a reentrantly curved path during each stitch-forming cycle of operations.
20. In a sewing machine, in combination, stitch-forming and thread-controlling mechanism including a thread-engaging member and an actuating element therefor, said actuating element comprising a pivotal crank provided with two arms, the pivot and a point spaced therefrom on one of said arms confined to move in eccentrically disposed circular paths, and the other arm having a connection with said thread-engaging member.
21. In a sewing machine, in combination with stitch-forming mechanism, thread-controlling mechanism including a thread-engaging member, means for moving the thread-engaging member to govern the thread as demanded by the stitch-forming mechanism including a member connected to the thread-engaging member, and means for moving said second member comprising a crank mounted on a pivot movable in a curved path, and means including an eccentric for turning the crank on the pivot as it traverses said path.
22. In a sewing machine, in combination with stitch-forming mechanism, thread-controlling mechanism including a thread-engaging member, means for moving the thread-engaging member to govern the thread as demanded by the stitch-forming mechanism including a member connected to the thread-engaging member, and means for imparting to said second member movement whereby a point on said member spaced from said connection is given a rotary motion about a fixed axis and a motion transverse with respect to said fixed axis to control the action of the thread, said latter means comprising a crank mounted on a pivot movable in a curved path, and means including an eccentric for turning the crank on the pivot as it traverses said path.
23. In a sewing machine, in combination with stitch-forming mechanism, thread-controlling mechanism including a pivoted thread-engaging member, means for moving the thread-engaging member to govern the thread as demanded by the stitch-forming mechanism including a member having a pivotal connection with said thread-engaging member, and means for imparting movements to said second member comprising a crank mounted on a pivot movable in a curved path, and means including an eccentric for turning the crank on the pivot as it traverses said path.
24. In a sewing machine, in combination, stitch-forming mechanism, a thread-control mechanism including a thread-engaging member, a link connected to the thread-engaging member, and means for moving said link comprising a crank mounted on a pivot movable in a curved path, and means including an eccentric for turning the crank on the pivot as it traverses said path.
- In testimony whereof, I have signed my name to this specification.
- PARK A. HERR.
